Primary Examiner — Jennifer Rivard(74) *Attorney, Agent, or Firm* — Arthur M. Peslak, Esq.; Gertner Mandel & Peslak, LLC(57) **CLAIM**

What is claimed is the ornamental design for a hairband holder, as shown and described.

DESCRIPTION

FIG. 1 is of a front isometric view of the hairband holder of the present invention,

FIG. 2 is a front plan view thereof.

FIG. 3 is a rear plan view thereof.

FIG. 4 is a side plan view thereof.

FIG. 5 is a side plan view thereof.

FIG. 6 is a top plan view thereof; and,

FIG. 7 is a bottom plan view thereof.

The broken lines shown in the drawings illustrate the environment of the article and form no part of the claimed design.
